UNITED STATES PATENT OFFICE

145,772

DESIGN FOR A MOTORCYCLE

Frank Brogan, Cincinnati, Ohio

Application December 3, 1945, Serial No. 124,275

Term of patent 14 years

(Cl. D90—8)

To all whom it may concern:

Be it known that I, Frank Brogan, a citizen of the United States of America, residing at Cincinnati, in the county of Hamilton, State of Ohio, have invented a new, original, and ornamental Design for a Motorcycle, of which the following is a specification, reference being had to the accompanying drawing, forming part thereof.

Fig. 1 is a side elevational view of a motorcycle, showing my new design.

Fig. 2 is a front perspective view of the same.
Fig. 3 is a rear perspective view thereof.

The characteristic features of my design reside in the portion shown by means of full lines in the drawing.

I claim:

The ornamental design for a motorcycle, as shown and described.

FRANK BROGAN.
